US0D1098426S

(12) **United States Design Patent** (10) **Patent No.:** **US D1,098,426 S**
(45) **Date of Patent:** **** Oct. 14, 2025**

(54) **EAR DROPS DISPENSING DEVICE**

(71) Applicant: **KING SAUD UNIVERSITY**, Riyadh (SA)

(72) Inventor: **Abdulrahman M. Alnuaim**, Riyadh (SA)

(73) Assignee: **KING SAUD UNIVERSITY**, Riyadh (SA)

(**) Term: **15 Years**

(21) Appl. No.: **29/990,468**

(22) Filed: **Feb. 21, 2025**

Related U.S. Application Data

(62) Division of application No. 29/887,173, filed on Mar. 17, 2023, now Pat. No. Des. 1,071,199.

(57) **CLAIM**

The ornamental design for an ear drops dispensing device as shown and described.

DESCRIPTION

FIG. 1 is a perspective view of first embodiment of an ear drops dispensing device showing my new design;

FIG. 2 is a front view thereof;

FIG. 3 is a rear view thereof;

FIG. 4 is a left side view thereof, the right side being a mirror image thereof;

FIG. 5 is a top view thereof;

FIG. 6 is a bottom view thereof;

FIG. 7 is a perspective view of second embodiment of an ear drops dispensing device showing my new design;

FIG. 8 is a front view thereof;

FIG. 9 is a rear view thereof;

FIG. 10 is a left side view thereof, the right side being a mirror image thereof;

FIG. 11 is a top view thereof; and,

FIG. 12 is a bottom view thereof.

1 Claim, 12 Drawing Sheets
